CLAIM

The ornamental design for a coordinate input device, as shown and described.

DESCRIPTION

FIG. 1 is a front bottom right perspective view of a coordinate input device according to a first representative embodiment of my new design, wherein support legs of the coordinate input device are in a first position;

FIG. 2 is a rear top left perspective view of the coordinate input device of FIG. 1;

FIG. 3 is a front view of the coordinate input device of FIG. 1;

FIG. 4 is a rear view of the coordinate input device of FIG. 1;

FIG. 5 is a top view of the coordinate input device of FIG. 1;

FIG. 6 is a bottom view of the coordinate input device of FIG. 1;

FIG. 7 is a left view of the coordinate input device of FIG. 1;

FIG. 8 is a right view of the coordinate input device of FIG. 1;

FIG. 9 is a rear top left perspective view of the coordinate input device of FIG. 1, wherein the support legs of the coordinate input device are in a second position;

FIG. 10 is a rear view of the coordinate input device of FIG. 9;

FIG. 11 is a top view of the coordinate input device of FIG. 9; and,

FIG. 12 is a right view of the coordinate input device of FIG. 9.

The broken lines in the drawings show portions of the coordinate input device that form no part of the claimed design.
